UNITED STATES PATENT OFFICE

CHARLES E. DATH, OF CHICAGO, ILLINOIS, ASSIGNOR TO W. H. MINER, INC., OF CHICAGO, ILLINOIS, A CORPORATION OF DELAWARE

DOOR CONSTRUCTION

Application filed May 15, 1931. Serial No. 537,613.

This invention relates to improvements in door construction.

One object of the invention is to provide a door construction especially adapted for refrigerator cars, comprising a one-piece door for closing the usual door opening, and means for swingingly supporting the door on the car, wherein hinge means is employed for pivotally supporting one end of the door for swinging movement to open and close the same, while the other end is properly guided to enter the door opening when closing the door.

A further object of the invention is to provide a construction of the character described in the preceding paragraph, wherein operating mechanism in the form of a rotary locking bar cooperating with keepers is provided at the hinged end of the door for forcing the same into the door opening, and means is also provided at the other end of the door, rigid with the latter, cooperating with fixed keepers on the car for wedging that end of the door inwardly.

Other objects of the invention will more clearly appear from the description and claims hereinafter following.

In the drawing, forming a part of this specification, Figure 1 is an elevational view showing my improved door construction as employed in connection with a refrigerator car for closing the usual door opening located in the side wall thereof. Figure 2 is a horizontal sectional view, corresponding substantially to the line 2--2 of Figure 1. Figure 3 is a horizontal sectional view, corresponding substantially to the line 3--3 of Figure 1. And Figure 4 is a detailed perspective view of a combined bearing and wedge bracket employed in connection with my improved door. In said drawing, 10 designates the side wall of a refrigerator car provided with the usual door opening 11. The door opening has the walls thereof beveled, as clearly shown in Figure 2, and the meeting edges of the door and walls of the door opening have the usual insulation employed in connection with cars of this type. A one-piece door 12 of any well-known design is employed to close the door opening 11.

My improved door construction comprises broadly a single door 12; a pair of double-jointed hinge members A--A for swingingly supporting the door along one edge; a guide bar B having crank means at opposite ends thereof and supported for rotation on the door; a pair of guide brackets C--C with which the guide bar B cooperates; a pair of combined supporting and wedge brackets D--D which rotatably support the bar B; a pair of fixed keeper members E--E which cooperate with the combined bearing and wedge brackets D--D; a rotary operating bar F having keeper engaging means at opposite ends thereof and forming a pivot means for the hinge members A--A; a pair of bearing brackets G--G for supporting the operating bar F on the door; a pair of keeper brackets H--H cooperating with the operating bar; and an actuating lever J pivoted to the operating bar F.

The hinge members A--A are of like construction, each comprising a hinge plate 13 fixed to the side wall of the car, and a hinge link 14 journaled at its outer end on the operating bar F. The hinge plate 13 is provided with a pair of spaced hinge eyes 15--15, and the hinge link 14 is provided with a pair of complementary eyes 16--16. The eyes of the hinge members 13 and 14 are connected by the usual hinge pin 17 extending therethrough. At the outer end the hinge link 14 is provided with a pair of spaced bearing lugs 18--18 which have journal openings 19 therein cooperating with bearing means on the operating bar F, as hereinafter more fully pointed out. The bearing lugs 18--18 are preferably in the form of hook members, as clearly shown in Figure 2, which are open at opposite sides. The links 14--14 of the two hinge members A--A are preferably of a length corresponding to one-half the width of the door opening. As will be evident, when the door is swung to open the same the connection of the hinge members A--A with the door will cause the corresponding end portions of the latter to swing outwardly away from the door opening in the arc of a circle corresponding in length to the length of the hinge links 14--14. Thus the maxi-

mum outward movement of the door laterally away from the car will not exceed a distance greater than one-half the width of the door opening. As will be evident, this corresponds to the maximum lateral outward projection of one of the usual double doors employed in connection with refrigerator cars for closing the door opening.

The brackets G—G which rotatably support the bar F are of similar design and are arranged at the top and bottom of the door adjacent to the right-hand vertical end edge thereof, as clearly shown in Figure 1. Each of the supporting bearing brackets G comprises a plate-like section which is fixed to the outer side of the door, and a pair of bearing lugs 19—19 which are of similar design to the bearing lugs 18—18 of the hinge links 14—14. The operating bar F comprises a central portion of rectangular cross-section to which end members 20—20 are fixed. Each end member comprises a cylindrical portion 21 which extends through the bearing lugs 19—19 of the corresponding bearing bracket G and the bearing lugs 18—18 of the corresponding hinge link 14. At the inner end each member 20 is preferably provided with a forked portion 22 which embraces the corresponding end of the central member of the operating bar F and is riveted thereto, as clearly shown in Figure 1. At the outer end each member 20 is provided with a crank portion 23 of well-known construction which cooperates with the corresponding keeper bracket H. As will be evident, the rotary operating bar F in addition to serving as means for actuating the door also functions as pivot means for the outer ends of the links 14—14 to connect the latter to the door. The keeper brackets H—H are of well-known design, having the usual cam grooves with which the crank members 23 of the bar F cooperate. The keeper members H—H are arranged respectively above and below the door and are fixed to the side wall of the car. The bar F is actuated by the usual hand lever J which is pivoted thereto, as indicated at 24. The lever J cooperates with the usual latch means, indicated by 25, and is sealed thereto by the usual car sealing member when the door is locked.

The guide bar B comprises a main portion 26 which is of round cross-section and has offset members 27—27 at the top and bottom ends thereof forming crank elements. At the outer ends the offset elements 27—27 are provided with crank portions proper 28—28 which are guided in the brackets C—C. The bar B is rotatably supported at the left-hand end edge of the door, as shown in Figure 1, by means of the combined bearing and wedge brackets D—D. Each wedge bracket D, as most clearly shown in Figure 4, comprises a plate-like portion which is secured to the outer side of the door. Any well-known se-

curing means may be employed, bolts being shown in this instance. The plate member of each bracket D has a pair of spaced vertically aligned lugs 29 and 30 thereon. The lug 29 is in the form of a hook which opens laterally inwardly. The lug 30 which is also in the form of a hook opens in the reverse direction to the hook of the lug 29. At the outer side of the bracket, the hook member 29 is enlarged, as indicated at 50, said enlarged portion being of wedge shape, as clearly shown in Figure 4. The bearing lugs 29 and 30 of each bracket D receive the corresponding end of the bar B and rotatably support the same on the door. In order to prevent vertical displacement of the bar B when mounted on the brackets D—D, the former is provided with a pair of fixed collars 31—31 which bear respectively on the outer bearing lugs of the two brackets, as clearly shown in Figure 1.

The fixed keeper brackets E—E are secured to the side wall of the car adjacent to the left-hand vertical wall of the door opening 11, as shown in Figures 1 and 2. Each bracket E comprises a plate section by which it is secured to the side wall of the car, screws being preferably employed for this purpose. Each bracket E also has a laterally extending, inclined flange-like section 32 which extends away from the side wall of the car and toward the door opening. The sections 32—32 of the brackets E—E form engaging elements with which the wedge portions 50—50 of the combined bearing and wedge brackets D—D cooperate.

The guide brackets C—C are in the form of elongated castings which are of similar design. As clearly shown in Figure 1, the guide brackets C—C are located respectively above and below the door opening and are secured to the side wall of the car. Each bracket is preferably provided with a plurality of securing ears 33—33—33 which receive securing elements for fastening the brackets. Each bracket C has an elongated guide slot 34 therein which cooperates with the corresponding crank portion 28 of the bar B. The guide slot 34 of each bracket is defined by spaced vertical side walls and transverse connecting end walls, the guide of the upper bracket C opening downwardly and that of the lower bracket C opening upwardly. The arms 27—27 of the crank portions of the bar B are of such a length that when the door is swung to either open or close the same the corresponding end thereof will be properly guided so as to enter the door opening and engage the wedge members 50—50 of the brackets D—D in back of the inclined flanges 32—32 of the keeper brackets E—E.

In opening the door, the operating bar F is rotated by the lever J, thus wedging the corresponding end of the door outwardly through the action of the crank members at

the upper and lower ends of the bar F which cooperate with the cam slots of the keepers H—H. When the door has thus been freed from the door opening by the outward wedging action of the rotary operating bar F, the brackets D—D will have been withdrawn from wedging engagement with the brackets E—E. When the door has thus been freed from the door opening, the operator completes the opening of the same by swinging the same on the hinge members A—A. During this action the left-hand end of the door, as viewed in Figure 1, will be guided in its movement by the bar B, through the medium of the crank members engaged in the guide brackets C—C. During this action the door will swing outwardly away from the side wall of the car and toward the right, as viewed in Figure 1, until it assumes the dotted line position shown in Figure 2. When in this position, the door opening is entirely cleared. The crank members of the bar B serve to guide the corresponding end of the door and prevent excessive lateral outward swinging movement of the same. As will be evident, the links 14—14 of the hinge members A—A restrict the lateral outward movement of the door away from the side wall of the car so that the same will not exceed a distance corresponding to one-half the width of the door opening or single door member 12.

In closing the door, the same is manually swung from the dotted line position shown in Figure 2 in the direction of the door opening. As the left-hand end of the door, as viewed in Figures 1 and 2, is guided by means of the bar B having the crank portions at the top and bottom ends thereof cooperating with the guides C—C, the door will be carried into the door opening 11, and the wedge portions 50—50 of the combined bearing and wedge brackets D—D will be engaged in back of the flanges 32—32 of the keepers E—E. When the door has been thus positioned, the crank members of the rotary operating bar F will be in position to cooperate with the slots of the keepers H—H. At this stage of the door-closing operation the bar F is rotated by means of the lever J so as to force the door tightly into the door opening 11. Due to the action of the operating bar F and the wedging of the door into the door opening at the corresponding end thereof, the wedge members 50—50 of the brackets D—D cooperating with the wedge faces of the brackets E—E will force the left-hand end portion of the door into the door opening. When completely closed, the operating bar F is locked in the usual manner by the latch means of the bracket 25 which cooperates with the lever J.

I have herein shown and described what I now consider the preferred manner of carrying out my invention, but the same is merely illustrative and I contemplate all changes

and modifications that come within the scope of the claims appended hereto.

I claim:

1. In door construction for refrigerator cars having a member provided with a door opening, the combination with a single door for closing said opening; of hinge arms pivoted at opposite ends to fixed pivots on the door and car respectively swingingly supporting the door along one edge; movable crank means including arms having crank pins at the outer ends, said crank means being rotatably mounted on the door for supporting the latter along the opposite edge; and guide means on the car for guiding said crank pins lengthwise of the car along said door opening.

2. In door construction for refrigerator cars having a member provided with a door opening, the combination with a single door for closing said opening; of hinge link members for swingingly supporting one end of the door, each of said hinge link members having the door swingingly supported at one end thereof and being swingingly supported on the car proper at the other end, said links being of a length at least equal to one-half the width of the door opening; fixed keeper means on the car; and means at the other end of the door engageable in back of said keeper means to force the door into said door opening when being closed.

3. In door construction for refrigerator cars having a member provided with a door opening, the combination with a single door for closing said opening; of hinge link members for swingingly supporting one end of the door, each of said hinge link members having one end swingingly supported on the car proper and swingingly supporting the door at the other end, said links being of a length at least equal to one-half the width of the door opening; fixed keeper means on the car; means at the other end of the door engageable in back of said keeper means to force the door into said door opening when being closed; and operating means on the door for closing and forcing the same into said opening.

4. In door construction for refrigerator cars having a member provided with a door opening, the combination with a single door for closing said opening; of hinge link members for swingingly supporting one end of the door, each of said hinge link members having one end swingingly supported on the car proper and swingingly supporting the door at the other end, said links being of a length at least equal to one-half the width of the door opening; fixed keeper means on the car; means at the other end of the door engageable in back of said keeper means to force the door into said door opening when being closed; and operating means at the

hinged end of the door for forcing said door open or closed.

5. In door construction for refrigerator

- cars having a member provided with a door opening, the combination with a single door for closing said opening; of hinge arms swingingly supported on the car and pivoted at their outer ends to one edge of the door to support said door for swinging movement with respect to said arms; movable pivot means mounted for eccentric swinging movement on the door at the opposite edge of the door; guide means on the car, within which said pivot means is movable, for guiding said pivot means lengthwise of the car along said door opening; keeper engaging means fixed to the last named edge of the door; and fixed keeper engaging members on the car with which said keeper engaging means have wedging engagement to force the door closed.

6. In a door construction for refrigerator cars having a member provided with a door opening, the combination with a single door for closing said opening; of hinge means

- swingable with respect to the door and swingingly supported on the car for supporting the door along one edge; eccentric pivot means for supporting said door along the opposite edge; guide means on the car for guiding said eccentric pivot means lengthwise of the car along said door opening; keeper means fixed to the car adjacent to the door opening and cooperating with said last named edge of the door to wedge the same into the door opening; and a door operator mounted on the door adjacent to said hinged edge for forcing the door open or closed.

7. In door construction for refrigerator cars having a member provided with a door

- opening; of a single door for closing said opening; a hinge member swingingly supported on the car and having the door swingingly connected thereto for supporting said door at one end; fixed keepers above and below the door opening; rotary operating means mounted on the door and having keeper engaging means cooperating with said keepers to force the door open or closed; guideways above and below said door opening extending lengthwise of the car; crank means rotatably mounted on the end of the door opposite to the hinged end thereof, said crank means having offset crank portions slidably guided in the guideways; bearing brackets fixed to the door for supporting said crank means thereon, each of said brackets having keeper engaging projections; and additional fixed keeper means on the car in back of which said keeper engaging projections engage to wedge the corresponding end of the door into the door opening.

In witness that I claim the foregoing I have hereunto subscribed my name this 13th day of May, 1931.
